UNITED STATES PATENT OFFICE.

REID L. WATTS, OF ROCK ISLAND, ILLINOIS.

CHIROPRACTIC OUTFIT.

1,413,547.

Specification of Letters Patent. Patented Apr. 18, 1922.

Application filed April 13, 1921. Serial No. 460,934.

To all whom it may concern:

Be it known that I, REID L. WATTS, a citizen of the United States, residing at Rock Island, in the county of Rock Island and State of Illinois, have invented certain new and useful Improvements in Chiropractic Outfits, of which the following is a specification.

This invention relates to tables and the primary object of the invention is to provide an improved portable and collapsible chiropractic table, which will be of rigid and strong construction, and which is not tilt-able when in its set up position.

In the chiropractic profession, a collapsible table which can be readily carried around is very essential to the chiropractor in making house calls, and in reality the collapsible table takes the place of the physician's medicine case.

It is therefore an object of the invention, to not only provide a collapsible table, which will be of strong and durable construction, but to also provide a table, which can be collapsed to simulate the appearance of an ordinary suit case or a physician's medicine case, and which will be just as easy to carry around as a suit case.

A further object of the invention is to provide a collapsible and portable chiropractic table, which will form a firm support for the patient, and permit the ready and easy working upon the patient by the chiropractor.

A still further object of the invention is to provide a strong, collapsible, nontiltable chiropractic table of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a side elevation of the improved chiropractic table in its collapsed portable condition.

Figure 2 is a side elevation of one section of the improved table.

Figure 3 is a side elevation of the other section of the improved table.

Figure 4 is a plan view of one section of the improved table showing the legs thereof in its collapsed position.

Figure 5 is a similar view of the other section.

Figure 6 is a transverse section through both sections of the table in their collapsed assembled position.

Figure 7 is an enlarged fragmentary section through one of the portions of the table showing the legs thereof in their extended operative position.

Figure 8 is a detail section taken on the line 8-8 of Figure 7.

Referring to the drawings in detail, wherein similar reference characters designate corresponding parts throughout the several views, the letter A indicates the head section, and B the body section.

The head section A is adapted to extend at a slight incline to the horizontal, while it is preferred that the body section B extend in parallel relation to the horizontal, and the patient is adapted to recline upon the sections A and B, with his head and shoulder upon the section A and his thighs and legs upon the section B. Thus it can be seen that his abdomen lies freely between the sections A and B.

The sections A and B are of substantially the same construction, and the section A includes a top wall 10, substantially rectangular in configuration, and walls 11, depending side walls 12, and inwardly extending retaining strips 13. These retaining strips 13 are carried by the lower edges of the side walls 12, and are of a wedge shaped construction, so as to define therebetween a tapered opening 14.

The inner surface of the wall 10 adjacent to the forward end thereof carries a pair of bearings 14, which are arranged in angular relation to each other. These bearings 14 rotatably support the angled ends 15 of the legs 16. The opposite end of the wall 10 is adapted to receive the bearing plates 17, which has swivelly mounted thereon by means of pins 18 the bearings 19, which rotatably and slidably supports the angled ends 20 of the legs 21. The pair of legs 21 and the legs 16 are preferably formed of tubing, but it is to be understood that I am not to be limited to this construction. The legs 21 have their angled ends 20 slidably mounted in the bearings 19 so as to permit

the same to be slid inwardly toward each other, so that they can readily lie between the legs 16 and also the swivelling of the bearings 19 permits its ready sliding movement.

5 The legs 16 are connected, by means of a pair of pivoted links 22, intermediate their end with the top 10.

10 The legs 21 are also pivotally connected intermediate their ends, by means of a pair of pivotally connected links 23. It is desirable that the outermost links 23 have their outer end slotted for the reception of the winged nuts and bolts 24, and if so desired 15 the legs 21 can also be slotted for the receiving of these bolts. This permits the easy and convenient collapsing of the legs 21 and also permits the inclination of the section A to be adjusted. It can be readily 20 seen by referring to Figure 3, that the legs 21 are relatively longer than the legs 16.

25 The section B includes a flat plate 25, the side longitudinal edges of which are arranged at an incline to the longitudinal center of the plate, and this forms a plate of substantially wedge-shaped configuration, which is adapted to fit between the inwardly extending flanges 13. The plate 25 is provided with side walls 26 which are 30 adapted to extend into section B between the flanges 17 and the end walls 27 which are fitted in the notched portion 28 of the end walls 11.

35 This section B also supports a pair of legs 29, and a pair of legs 30. The legs 29 are mounted in the same manner as legs 16, while the legs 30 are mounted in the same manner as the legs 21. Thus it can be seen that the legs of the section B can be folded in the 40 same manner as the section A. Also links 31 are provided for legs 29 similar to the links 22 and links 32 provided for the legs 30 which are arranged in the same manner as the links 23.

45 It is preferred that the active surfaces of the sections A and B be upholstered or covered with a suitable fabric or leather as at 33.

50 The section A has secured thereto on one of its longitudinal side walls 12 a suit case handle 35, whereby the device can be readily carried around when in its collapsed condition. In order to hold the sections A and B together in their assembled position when 55 the sections are collapsed, suitable clamps 36 are carried by the end walls of the sections. It can be seen that when the sections are arranged together as shown in Figures 1 and 6 of the drawings, that the appearance 60 thereof simulates a suit case, and that the same can be as easily carried around as a suit case.

65 In use of the improved table, when it is desired to set the same up the clamps 36 are unlatched, and the sections A and B taken

apart. The legs 16 and 29 of the sections A and B can be first opened if so desired, after which the legs 21 and 30 can be opened. These legs are adjusted to their desired position in their respective bearings, and the 70 thumb nuts of the connecting links 23 and 32 can be tightened.

75 In order to prevent accidental movement of the legs 30 in relation to each other, bolts 37 may be slidably carried by one of the angled ends of the legs. It is desirable that the sliding bolt be provided with a projecting lug 38, which carries a suitable winged nut 39 for holding the same in its adjusted position. The stud protrudes through the 80 slot 40 in the angled end of the mentioned leg. It can be seen that by loosening the wing nut 39, the bolt 37 can be slid into the other angled end of the other leg.

85 As stated, in the beginning of the description, the sections A and B are adapted to be so positioned in relation to each other that one of the same is adapted to support the head and shoulders of the patient, while the other section is adapted to support the thighs 90 and legs of the patient. These sections are so arranged and can be so positioned in relation to each other, that the body of the patient will be so arranged as to permit the convenient working thereon by the chiropractor. Owing to the means of mounting the legs on the sections, a relatively large spread is obtained therefor which will absolutely preclude the tilting of the sections of the table and add to the rigidity and 95 stability thereof.

100 From the foregoing description it can be seen that an improved collapsible and portable chiropractic table has been provided, which forms a neat and attractive appearance when in its collapsed position and which will form a strong and non-tiltable structure when in its set up position.

110 Changes in details may be made without departing from the spirit or scope of this 110 invention; but,

I claim:

1. A chiropractic table comprising a top wall, and depending side walls, bearings carried by the inner surface of the top wall 115 adjacent to the ends thereof, means swivelly securing certain of the bearings to the top wall, and swinging legs mounted in said bearings and adapted to normally lie inward of and between said side walls.

120 2. A chiropractic table comprising a top and depending side walls, bearings carried by the inner surface of the top adjacent to the ends thereof and disposed inward of and between the side walls, certain of the bearings being swivelly connected to said top, the legs having angled inner terminals rotatably mounted in said bearings, and means for holding the legs in their extended operative positions in relation to the top.

3. A chiropractic table comprising a top, a pair of bearings carried by the inner surface of the top adjacent to one end thereof, a pair of bearings swivelly carried by the 5 inner surface of the top adjacent to the other end thereof, legs for the top having inner angled terminals, the angled terminals of certain of the legs being mounted in said first bearings, the angled terminals of the 10 other legs being mounted in the second bearings for sliding and rotary movement, and means for holding the legs in extended position in relation to the top.
4. A chiropractic table comprising a top, 15 a pair of bearings arranged in angular relation carried by the inner surface of the top adjacent to one end thereof, a pair of bearings pivotally carried by the inner surface of the top adjacent to the opposite end thereof, legs having angular terminals rotatably mounted in said first bearings, certain of the legs having their angled terminals slidably as well as rotatably mounted in said 20 second bearings, and sliding bolts carried 25 by the terminals of certain of the legs for

engaging the terminals of adjacent legs when the same are in extended positions.

5. A chiropractic table comprising a top, a pair of bearings carried by the top and arranged in angular relation to each other 30 adjacent to one end of the top, a pair of legs having angular terminals rotatably mounted in said bearings, a pair of links pivotally connected together and to the legs and top, a second pair of bearings swivelly carried 35 by the inner surface of the top adjacent to the ends of the top remote from the first mentioned bearings, a second pair of legs having angular terminals slidably and rotatably mounted in said second mentioned bearings, 40 links pivotally connected together, means pivotally connecting the upper terminals of the inner links to the top, means slidably and pivotally connecting the free terminals of the links to the last mentioned legs, and 45 bolts carried by the angled terminal of one of the legs for engaging in the angled terminal of the other leg.

REID L. WATTS.
